and in Great Britain December 16, 1930

4 Claims. (Cl. 164—69)

The present invention relates to an apparatus for the manufacture of tubes from cardboard, paper or the like material.

In the making of containers by way of example, of cardboard or the like material, it has been usual to form a long tube and to cut up this tube into short sections by a hand operated machine.

According to the present invention lengths of cardboard or the like tube are cut up into short sections automatically upon a machine.

The tubes are automatically fed one at a time in timed sequence to a cradle by which they are fed upon a revolving mandrel. When the said tube is in position upon the mandrel cutting tools, such as rotary disc knives are automatically brought into engagement with the tube at a number of set distances along it. Means are subsequently put into operation for automatically stripping the severed lengths of tube from the mandrel.

The invention is more particularly described with reference to the accompanying drawings in which:—

25 Figure 1 is a side elevation of one form of construction of the machine.

Figure 2 is a corresponding plan view.

Figure 3 is an end elevation.

30 Figure 4 is a diagrammatic view of the cam path controlling the crosshead in its forward and backward travel and causing a dwell at each end of the forward and backward positions.

Figure 5 is a diagrammatic end view of a modification while

35 Figure 6 is a detail.

The frame consists of a bed plate 1 and vertical brackets 2, 3, 4 and 5. The brackets 3, 4 and 5 are interconnected by the crosshead guides 6 and 7. The mandrel 8 extends from the main 40 driven shaft 9 which rotates in suitable bearings in the vertical brackets 2 and 3 of the frame, and also a further bearing 10 having a projection 11 is rotatably mounted in the rear crosshead bracket 12 to engage the recess 13 in the 45 end of the mandrel 8 during the operation of severing the tubes.

A drum 14 carrying a cam track 15 is secured to the shaft 16 which is rotatably mounted in bearings in the parts 2, 3 and 4 of the frame and 50 is driven from the main shaft 9 through two sets of toothed wheels 17, 18, 19 and 20. The pinion 17 on the main shaft 9 engaging the toothed wheel 18 secured to the counter shaft 21, which is rotatably mounted in the parts 2 and 3 of the frame. The cam track 15 takes the

form of a channel section the vertical walls of which engage a roller 22 mounted on the underside of the crosshead bracket 38 forming part of the carriage or cradle. It will be understood that normally only one of the said vertical walls engage the roller 22 during the traversing operation. A set of pivotal levers 23 are interconnected at their lower ends by toothed segments 24 so that when the roller 22 is travelling in the direction of the arrow 25 the roller 22 engages the ends of the first pair of pivotal levers 23 to open these to form a guiding wall, whereupon the other pair of pivotal levers rotate towards them to completely close the gap from the reverse track as indicated by chain dotted lines 65 in Figure 4 of the drawings.

The diagonally arranged portions 15a and 15d of the cam track 15 effect the traversing action of the carriage or cradle 26 while the circumferential portions 15b and 15c at the ends of the drum 14 cause the carriage or cradle 26 to rest or dwell for a predetermined period of time. During the rest period at the end 15b of the cam track 15, rotary cutting knives 27 which are adjustably mounted on the bracket 28 secured 70 to the shaft 29 are moved into engagement with the long length of tube revolving with the mandrel 8 to cut this tube into short lengths by engagement of the lever 30 through its roller 31 with the cam wheel 32. The cam wheel 32 is 75 secured to the shaft 33 to which is also secured the toothed wheel 34 engaging the pinion wheel 35 on the drum shaft 16 so that these parts are synchronized. The rotary knives 27 are returned to the inoperative position by the spring 80 36 attached to the frame.

The resultant severed short pieces of tube are stripped off by the projection 37 of the crosshead bracket 38.

The crosshead brackets 12 and 38 are interconnected by stay bolts 39 to form a cradle or carriage 26 for the reception of the long length of tube from the chute or guide 40. The chute 40 is fed from any suitable conveyor (not shown) and has stops 41 in the form of upstanding levers secured to spindles 42 rotatably mounted on the guideway or chute 40 with a further set of stops 43 secured in spaced relationship with the stops 41 to the spindles 42 and substantially at 90°, so that when the stops 41 are rotated 100 through 90° to release a length of tube from the guideway 40 the second pair of stops 43 project upwards to prevent more than one tube being released to enter the cradle 26. Therefore it will be understood that the interval between the pairs 105 110

of stops 41 and 43 is slightly greater than the diameter of a tube so that the second pair of stops 43 rocks up to temporarily hold the tubes in the guideway 40 behind the one which is 5 being delivered into the cradle 26.

The stops 41 are normally vertical due to the action of the spring 44 secured at one end to the parts 4 and 5 of the frame. The stops are rotated through 90° to release a long length of 10 tube by a projection 46 on the crosshead bracket 12 which engages a projection 47 when the cradle or carriage is travelling to the charging or starting position.

The cradle or carriage 26 consists of two cross-head brackets 12 and 38 interconnected by stay bolts 39 (as previously stated) which brackets 12 and 38 slidably engage the guide portions 6 and 7 of the frame. The leading crosshead bracket 38 has a roller 22 mounted below to 20 engage the cam path 15 on the drum 14 to cause the cradle or carriage 26 to be traversed forward and backward. The tube when released from the chute or hopper 40 drops upon two pivotal radial sections 48 which holds this to act as a 25 guide together with the fixed radial portion 49 arranged at the lower end of the chute 40 thus serving to support and guide the cardboard or like tube until it is transferred to the mandrel. Immediately after the tube has been received in the cradle 26 the roller 22 engaging the 30 cam track 15 leaves the circumferential portion 15c of the track and is displaced longitudinally of the machine by the diagonally arranged guide 15a on the drum to transfer the tube from the cradle or carriage 26 to the mandrel 8 by the 35 aid of a guide or abutment 10a arranged on the rear crosshead bracket 12, the portion 11 of this abutment serving as a bearing for the mandrel 8 during the cutting operation.

40 The guide or abutment 10a rotates in a ball bearing so that the cardboard or the like tube is free to rotate with the mandrel 8 during the operation of pushing the tube on to the mandrel. The front bracket 38 of the cradle 26 has 45 mounted upon it a slidable portion 38a which at the end of its forward travel engages the adjustably fixed stop 54 on the part 4 of the frame, which is caused to move out of its normal relationship with the bracket 38, being normally held by a spring 38b, so that while the tube is 50 free to drop between the front and rear crosshead brackets 38 and 12 respectively, the arrangement just described closes the gap, between the stops thereby ensuring that the tube with its printed labels is in the correct relationship with the rotary cutting knives 27 to sever these tubes and also to trim very short lengths of tube from the ends of long tube.

60 The cutting operation is effected during the rest period of the cradle or carriage 26 at the forward end of its stroke and, immediately after the cutting knives 27 have been rocked into the inoperative position the stripping operation is 65 effected by engagement of the portion 37 of the slidable portion 38a of the bracket 38 with the tube when the carriage is travelling on its return stroke.

70 During the forward movement of the cradle or carriage 26 the radial portions 48, which are pivotally mounted, are rotated through an arc equal to about 90° by a projection 50 at their lower ends engaging a fixed stop 51 on the part 4 of the frame so that during the return of the carriage or cradle 26 to cause the stripping the radial portions 48 do not impede the delivery

80 of the short length of tube after leaving the mandrel 8. The radial guides 48 are returned to their operative position just before the carriage or cradle 26 reaches the charging position by the engagement of another projection 52 with another fixed stop 53 on the frame.

85 The mode of operation is as follows:—

The chute or guide 40 is filled with tubes from a suitable conveyor means and the machine which includes the mandrel 8, the drum 14 carrying the cam track 15 for the traversing action and the cam wheel 32 for the cutting operation, is set in motion, all movements being synchronized.

90 It will be assumed that a tube has been fed into the cradle 26 during one of the dwell periods of the traversing members corresponding to the position shown in Figures 1 and 2 of the drawings, whereupon the roller 22 mounted in the underside of the bracket 38 is transferred from the circumferential portion of the cam track 15c to the diagonal portion 15a to cause the cradle or carriage 26 to move forward to place the tube upon the mandrel 8 by engagement of the guiding portion 10a on the cross-head bracket 12, with one end of the tube. The stripping ring or collar 37 travels in front of the tube upon the mandrel 8 until the slidable portion 38a of the crosshead bracket 38 engages the stop 54 on the part 3 of the frame allowing the gap between the stripping projection or ring 37 to be closed up. By this time the roller 22 has been transferred from the diagonally arranged cam track 15a to the circumferential portion 15b of the cam track 15 to cause the 100 necessary dwell. During the forward travel the radial guides are rocked through 90° ready for the return journey. The rotary knives 27 which are timed for the arrival of the tube are rocked forward to sever the tube into the desired short lengths by the roller 31 on the lever 30 engaging the cam wheel 32 the spring 36 returning the knives 27 to their rest position immediately afterwards. The roller 22 is transferred from the circumferential portion 15b of the cam track 105 15 to the reverse diagonal portion 15d to carry the cradle or carriage 26 and consequently the stripping bracket 37 backwardly to deliver the short tubes into a receptacle or chute. The projection 47 on the lower part of the stops 41 engage a projection 46 to cause a long length of tube to be fed on to the radial guides 48 which have also been returned to their normal position on the return journey by the projection 52 engaging the stop 53 whereupon the cycle of 110 operation is repeated automatically.

115 In a modification of the invention a pair of mandrels 60, 61 are employed being operated from one source and employing only one drum 62 to effect the traversing of the cradles or carriages 63 as illustrated diagrammatically in Figure 5 of the drawings.

120 We declare that what we claim is:—

125 1. A machine for cutting up lengths of cardboard or like tube into relatively short sections comprising a rotatable mandrel, a cradle adapted to receive lengths of tube one at a time, a rotatable drum having a cam track formed therein, an actuating member extending from said cradle and engaging in said cam track to cause displacement of the cradle longitudinally of the mandrel for delivering and withdrawing tubes to and from the mandrel, a plurality of knives movable towards and away from the mandrel and means for automatically displacing said 130

knives towards the mandrel to cut the tube into sections whilst rotating with the mandrel.	and away from the mandrel and means for automatically displacing said knives towards the mandrel to cut the tube into sections whilst rotating with the mandrel.
2. A machine for cutting up lengths of cardboard or like tube into relatively short sections comprising a rotatable mandrel, a cradle adapted to receive lengths of tube one at a time, a rotatable drum having a cam track formed therein, a roller supported from said cradle and engaging in said cam track to cause displacement of the cradle longitudinally of the mandrel for delivering and withdrawing tubes to and from the mandrel, a plurality of knives movable towards and away from the mandrel and means for automatically displacing said knives towards the mandrel to cut the tube into sections whilst rotating with the mandrel.	4. A machine for cutting up lengths of cardboard or like tube into relatively short sections comprising a rotatable mandrel, a cradle adapted to receive lengths of tube one at a time, a rotatable drum having a cam track formed therein, an actuating member extending from said cradle and engaging in said cam track to cause displacement of the cradle longitudinally of the mandrel for delivering and withdrawing tubes to and from the mandrel, said cam track comprising circumferential portions one at each end of the drum adapted to cause the cradle to dwell for a predetermined period of time at each end of its stroke and inclined portions connecting diagonally opposite ends of said circumferential portions adapted to cause traversing of the cradle, pairs of gate members at the junction of said inclined cam track portions adapted to be simultaneously displaced by engagement therewith of said actuating member from a position in line with one track portion to a position in line with the other track portion, a plurality of knives movable towards and away from the mandrel and means for automatically displacing said knives towards the mandrel to cut the tube into sections whilst rotating with the mandrel.
